JOHN F. MARTIN, OF SPRINGFIELD, MASSACHUSETTS, ASSIGNOR TO AMERICAN BOSCH MAGNETO CORPORATION, OF SPRINGFIELD, MASSACHUSETTS, A CORPORATION OF NEW YORK

ADJUSTING DEVICE FOR MAGNETOS

Application filed January 24, 1930. Serial No. 423,228.

My invention relates to adjusting devices for magnetos, particularly magnetos used for ignition purposes in connection with internal combustion engines.

5 In the operation of such a magneto, the spark for ignition must of course be delivered at a definite point in the cycle of movement of the parts.

If the magneto is of the bipolar type, with 10 a rotatable armature between its pole pieces, the armature having a suitable number of turns of wire thereon, the spark should be delivered when the trailing edge of each head of the armature is separated from the tip of 15 the adjacent pole piece,—for a very brief instant—by a predetermined space of interval, technically known as the “edge distance” of the magneto. When this “edge distance” is relatively small, for example, a little over 20 three millimeters for an ordinary magneto, and the circuit of the generating winding on the armature is opened by the circuit breaker or interrupter in corresponding position, the spark is “advanced” to the maximum degree; 25 and by increasing the edge distance and shifting the point of actuation of the circuit breaker accordingly, the spark can be more or less retarded. In practice, however, due to variations arising in the manufacture of 30 the circuit breaker of the magneto, the cam ring and other elements, the parts when mounted often fail to sustain to one another the relations necessary to perform accurately the function here described. Hence adjustment after the assembling of the magneto 35 must be permitted.

An object of the invention is to provide a simple and inexpensive device or appliance which can be readily attached to a magneto 40 and easily manipulated to afford the adjustment required.

A further object of the invention is to provide an adjustable device of this sort, capable of being properly secured to the front of a 45 magneto beneath the circuit breaker or interrupter thereof, and affording easy access when the position of the device is to be altered.

These and other objects and advantages of 50 the invention are set forth in the following de-

scription, taken with the drawings, and while I illustrate a preferred form of my invention, I of course reserve the right to make changes in details without exceeding the scope and spirit of the invention or departing 55 from the principle underlying same.

On the drawings:

Fig. 1 is a view in longitudinal section of the rear part of a magneto with a circuit breaker, and an adjusting device according 60 to my invention; Fig. 2 is a front sectional view thereof, taken on the line 2—2 in Fig. 1; Fig. 3 is a similar view showing the position of the armature and the edge distance for an “advanced” spark; and Figs. 4 and 5 are perspective views showing alternative forms of my adjusting device.

The same numerals identify the same parts.

The numeral 1 shows part of the frame work or housing of a magneto, which may be of the usual bipolar design, having permanent magnets, with lower ends shown at 2, extending upward from the base 3 of the housing 1. In the housing 1 is a rotatable armature 4, mounted between the polepieces 5. This armature has heads 6 and 7, with curved outer faces, connected by a core 8; and on the core between the heads is the winding (not shown) in which are generated the voltage and current. At one end the heads 6 and 7 are connected by a plate 9 having a trunnion or journal 10; and the adjacent end of the housing 1 has an inside recess containing an anti-friction bearing 11 engaging the trunnion 10. The opposite ends of the heads 6 and 7 are similarly connected to the drive shaft for the magneto, which is a solid spindle that can be united by a suitable coupling to the member that furnishes the power to operate the armature 4.

The end of the housing 1 supporting the journal 10 has an exterior projection 12 over which fits snugly a rimmed cap 13. This cap and projection mount the cylindrical casing 14 of the circuit breaker or interrupter, which has an actuating arm or lever 15 to enable it to be moved to assume different angular positions. This ring or casing 15 carries inside the cams which operate the circuit breaker, and by turning the casing 14 the spark can be 100

timed so as to advance it or retard it. The construction thus far described is well known. At its lowest point the casing 14 has a peripheral slot 16.

The circuit breaker comprises a disk 17 affixed to the shaft 10 by a bolt 18 and mounted to rotate freely in the casing 14. It bears insulation 19 on its face, and against this insulation is secured a contact piece 20. A screw 21 passes through the contact piece 20 and insulation 19, and engages the disk 17; but the screw is insulated from the aperture through which it passes in the piece 20, and its head is separated from the piece 20 by an insulating washer 22. Also a lock washer 23 may be added to keep the screw tight. In a projection 24 of the piece 20 is mounted an electrode 25. The bolt 18 passes through the contact piece 20 and makes contact therewith. It is insulated from the disk 17 and the shaft 10, and connected at its inner end to one terminal of the generating winding of the magneto in the usual way; the other terminal of this winding being grounded. On the disk 17 and in electrical connection therewith is a pivoted lever 26, carrying an electrode 27 cooperating with the electrode 25. When these electrodes are in contact the circuit is completed through the breaker lever 26, the disk 17, the housing or framework of the magneto, the generator winding by way of its grounded terminal, the bolt or stem 18, contact piece 20 and electrode 25. A spring 28 holds the lever 26 on its pivot; and the end opposite the electrode 27 bears a fibre insert 30 to be engaged by cam projections 31 and 32 on the inside of the casing 14, to be actuated thereby and thus separate the electrodes 25 and 27 when the instant of ignition is reached. These cams may be integral with the casing 14, or be made as internal projections on a separate ring 33, indicated in broken lines in Fig. 2 attached to the inside of the casing 14 and constituting with the cams and the casing 14 means for actuating the interrupter. A spring 34 affixed to the disk 17 at a suitable point 35 and to the lever 26 holds the electrodes 25 and 27 in engagement. The parts of the circuit breaker are of the usual construction and form no part of my invention.

When the cam projections 31 and 32 are set by the casing 14 to operate the breaker lever 26 at the most advanced point for the spark, the electrodes or contacts 25 and 27 will separate at the instant when the armature is passing through the position shown in Fig. 3. The direction of rotation is assumed to be clockwise when the armature is viewed from the end connected to the drive shaft; that is, counterclockwise when viewed as shown in Figs. 2 and 3. At the exact moment of ignition, the trailing edge of the head 6 will be separated from the adjacent tip of the nearest polepiece 5 by a space equal to that between the points 36 and 37 in Fig.

3; and the trailing edge of the head 7 will be separated from the adjacent tip of the other polepiece 5 by the same interval. This interval has already been mentioned above as the "edge distance"; and when the ring 14 is turned to cause the cams 31 and 32 to open the armature circuit at the electrodes 25 and 27 at any later point in the rotation of the armature, this "edge distance" is increased. The point of maximum advance for the spark is fixed by attaching to the end of the housing 1 below the casing 14 an adjusting device 38; which has slots 39 in its ends for screws 40. The adjusting device is secured against the end of the housing 1 in transverse position, and it has a central projection 41 on its upper edge which enters the slot 16 and abuts against the end of this slot at the right, as appears in Figs. 2 and 3, when the casing 14 is set to cause an advanced spark to be given by the circuit breaker. Hence, to set the circuit breaker at maximum advance position for the spark, one needs only to turn the casing with the arm 15 till the right hand end of the slot 16 abuts the projection 41.

However, variations are generally found when the magneto is assembled; and if the member 38 were in absolutely fixed position, the edge distance between the points 36 and 37 might be either too large, or too small, when the circuit breaker is set for advanced sparking with the right hand end of the slot 16 abutting the projection 41. Hence efficient operation for this point could not be had, and the magneto would also not perform at its best for other positions of the casing 14 and cams 31 and 32. Therefore the member 38 has its openings 39 elongated so that it can be shifted from one side of the magneto to the other. In Figs. 2, 3 and 4 these openings or slots lie on an arc concentric with the axis of rotation of the armature; and by the loosening of the screws 41, the device 38 can be adjusted so that the projection 41 is caused to occupy a true position which will enable the casing 14, when the right hand end of the slot 16 engages the projection 41, to hold the cams 31 and 32 in place to enable the breaker lever to operate at the exact point to give the edge distance its proper value.

In Fig. 5 the member 38 has slots 42 which are longitudinal, instead of lying on an arc concentric with the axis of rotation of the armature.

The casing 14 has a cover 43, and to the end of the magneto is fixed a post 44, bearing a pivoted spring arm 46 to engage the cover and keep it in place. The arm is swung aside when the cover is to be removed. A socket 47 on the disk 17 carries the usual carbon brush to engage the end of the magneto and insure a good ground connection for the disk 17 and the contact 27.

With the device 38 the edge distance can

be set with the greatest ease and accuracy by simply loosening and then tightening the screws 40, after shifting the device 38 in the required manner.

The member 38 as shown is plane or flat, and its ends with the slots 39 are widened. In the middle, where it has the projection 41, it is narrow enough to clear the post 44, and its upper edge may be concave and curved to some extent according to the curvature of the casing 14. When the slots 38 are straight and longitudinal as in Fig. 5, there will always be space enough between the upper edge of the member 38 and the casing 14 to allow adjusting movement of this member for the purpose above set forth.

The end of the magneto shown in Fig. 1 is integral with the housing; but the invention is just as well adapted for magnetos in which this end is separate and held on by screws or the like fastening means.

By the use of the adjustable stop plate 38, the disassembling and rechecking of the magneto, as well as any filing of the slot 16, are rendered unnecessary. The armature edge distance is set accurately and the plate is moved on the two screws 40 until the tongue 41 is brought against the end of the slot 16 at the right in Figs. 2 and 3. The screws 40 are then tightened and the plate 38 secured. Hence much time and labor in finishing the magneto are saved.

Having described my invention, what I claim is:

- 35 1. In a magneto, an interrupter, means for actuating the interrupter, and a plane member held against the end of the magneto and extending adjustably across said end, said member engaging said means to fix the edge distance of said magneto.
- 40 2. In a magneto, an interrupter, means for actuating the interrupter, and a plane member adjustably secured to the end of the magneto and engaging said means to adjust the edge distance of the magneto.
- 45 3. In a magneto, a rotatable interrupter, means for actuating the interrupter, a plane member disposed against the end of the magneto, a projection on said member to engage said means, slots in said member, and means on the magneto passing through said slots for securing the member to the magneto and permitting movement of said member to fix the edge distance of the magneto.
- 50 4. The combination according to claim 3 wherein the slots are straight and extend longitudinally of said member.
- 55 5. The combination according to claim 3 wherein the slots are curved and lie on an arc concentric with the axis of rotation of the interrupter.
- 60 6. In a magneto, a member for adjusting the edge distance, said member being plane or flat and having a projection on one edge.
- 65 7. In a magneto, a member for adjusting

the edge distance of the magneto, said member having wide ends with slots therein, a narrow mid-portion between said ends, and a lateral projection at said mid-portion.

8. In a magneto, a member for adjusting the edge distance of the magneto, said member having slotted ends and a concave edge, with a projection on said edge.

9. In a magneto, an interrupter, a casing having means to actuate the interrupter, the magneto having a projecting end received in said casing to support the latter, the casing having a slot in its lower side, a plane member secured flat against said end below said casing in transverse position, said member having a projection to enter said slot, the ends of said member also having slots, and means passing through said last named slots to hold the member adjustably against the magneto.

10. In a magneto, an interrupter, a casing adjustably mounted on the magneto to enclose the interrupter, a cover for the casing, a post attached to the magneto adjacent said casing, an arm on the post to hold the cover in place, and a device to fix the edge distance of the magneto, adjustably attached to the magneto between said post and said casing.

11. The combination according to claim 10, wherein said device has widened ends and a narrow portion in proximity to said post.

12. The combination according to claim 10, wherein said device has a projection adjacent said post to engage the casing.

In testimony whereof I affix my signature.

JOHN F. MARTIN.
